(57) **CLAIM**

The ornamental design for a front and rear door trim for a vehicle, as shown and described.

DESCRIPTION

FIG. 1 is a front left perspective view of a front and rear door trim for a vehicle according to the present invention.

FIG. 2 is a front right perspective view of the front and rear door trim shown in FIG. 1.

FIG. 3 is a rear right perspective view thereof.

FIG. 4 is a rear left perspective view thereof.

FIG. 5 is a front view thereof.

FIG. 6 is a rear view thereof.

FIG. 7 is a left side view thereof.

FIG. 8 is a right side view thereof.

FIG. 9 is a top view thereof.

FIG. 10 is a bottom view thereof; and,

FIG. 11 is a front view of the front and rear door trim shown in FIGS. 1-10, but with the front and rear door trim mounted on a vehicle, and the rest of the vehicle shown in de-emphasized and half-tone portions so as to illustrate environmental structure. These portions form no part of the claimed design. More particularly, in FIG. 11, the inventive front and rear door trim is shown within the broken line, and the elements shown outside the broken line form no part of the claimed invention, but are instead included to show environmental aspects thereof. The invention further contemplates a mirror image front and rear door trim on the opposite side of the vehicle.
